UNITED STATES PATENT OFFICE.

DANIEL B. TAMAGNO, OF NEW YORK, N. Y., ASSIGNOR TO LYDIE TAMAGNO, OF NEW YORK, N. Y.

FAUCET-CLOSURE FOR CANS.

1,075,611.

Specification of Letters Patent. Patented Oct. 14, 1913.

Application filed February 5, 1913. Serial No. 746,256.

To all whom it may concern:

Be it known that I, DANIEL B. TAMAGNO, a citizen of the United States of America, residing in the borough of Manhattan, city, county, and State of New York, have invented a certain new and useful Improvement in Faucet-Closures for Cans, of which the following is a specification.

This invention comprises a new organization of parts constituting a faucet particularly applicable to cans containing oils, alcohol, turpentine, etc.

In the accompanying drawing; Figure 1 is a partial top view of a can equipped with the invention: Fig. 2, a section on the line A, B, of Fig. 1; Fig. 3, a section on the line E, F, of Fig. 2; and Fig. 4, a section on the line C, D, of Fig. 2.

1 indicates the wall of an ordinary can which, as shown, may be taken to be the cover or upper wall. It may, however, be also considered as a bottom or side wall. In it is an opening into which is inserted a cup-shaped portion 2 having a surrounding flange 3 that overlies the outer face of the wall of the can, bears thereupon, and may be soldered thereto as indicated at 4. The countersunk portion 2 has extending from one of its side walls a hollow tapered horizontal valve seat portion 5 closed except for a port or ports opening into the interior of the can. Two such ports are shown, one, 6, through which contents of the can may pass and another, 7, to which is connected a vent pipe 8. The tapered or conical member 5 contains a lining or packing 9 having openings through it coincident with the ports 6, 7; and within it is seated a rotatable hollow conical valve plug 10 having in it a port 11 adapted to register with the port 6. The top of the valve plug is formed with a tubular extension 12 to which is secured a faucet 13; and the valve plug, closely and properly seated within the packing in the outer shell 5, is held in position by spinning or turning over as at 16 the upper or inner edge of the shell 5 upon the top of an interposed spring washer 17 bearing on the valve plug 10.

50 In the wall of the plug lengthwise thereof is a depression or channel 14 with which the vent pipe 8 is, of course, in communica-

tion and which at the inner or head end of the shell 5 communicates with the annular space formed by the turned over flange 16 and spring washer 17, which latter has apertures 15 opening to the well that is formed in the closure plate 2, 3. The relation of parts is such that, when the swinging portion is rearwardly within the well, 55 the vent is closed to the atmosphere; but, when drawn out for pouring, as in Fig. 4, the open well is in communication with the vent pipe, and, in the latter position, the ports 6 and 11 coincide so that contents of 65 the can may be poured through the faucet.

The spout in turning moves in a direction at an angle (preferably at a right angle as shown) to the direction in which contents of the vessel are poured and consequently 70 is held rigidly against strains in the opposite direction. This is a feature of value since when a can is raised and turned to pour the spout is apt to bear upon the rim of the receiving vessel. To remove any 75 fluid that will not pass out through the spout the can may be punctured.

All the parts of this device may be made of sheet metal, such as common tin, from appropriate dies and but little, if any, 80 soldering is required. The closure plate 2, 3, the valve parts and the faucet may all be completed and assembled at very small cost and applied to a wall of a can, or other vessel, in the manner described. 85

I claim:

1. A can closure adapted to be mounted in a wall of a can and comprising a countersunk well, a projection laterally therefrom constituting a valve member, a valve plug 90 turning therein and a spout carried by the plug and by which the latter is operated, the spout being disposed within the well when in non-pouring position and adapted to swing outward to pouring position in a 95 direction at an angle to the line in which contents of the can are discharged.

2. A can closure adapted to be mounted in a wall of a can and comprising a countersunk well, a hollow tapered valve member 100 extending from a wall of the well and having therein two ports, a vent pipe connected to one of said ports, a hollow tapered valve plug fitting and turning in said valve

member and having in its wall an external channel opening to the well and also a port adapted to register with the other port in said valve member, and a pouring spout secured to and communicating with its interior, said spout being depressed within the well when in non-pouring position and adapted to swing outward to pouring posi-

tion in a direction at an angle to the line in which contents of the can are discharged. 10

In testimony whereof, I have hereunto subscribed my name.

DANIEL B. TAMAGNO.
